UNITED STATES PATENT OFFICE.

GEORGE W. COPE AND WILLIAM L. BERTRAM, OF DETROIT, MICHIGAN, ASSIGNORS TO KALAMAZOO STOVE COMPANY, OF KALAMAZOO, MICHIGAN.

DESIGN FOR A RANGE.

SPECIFICATION forming part of Design No. 36,324, dated May 12, 1903.

Application filed October 4, 1902. Serial No. 125,993. Term of patent 7 years.

To all whom it may concern:

Be it known that we, GEORGE W. COPE and WILLIAM L. BERTRAM, citizens of the United States, residing at the city of Detroit, in the county of Wayne and State of Michigan, have invented a new, original, and ornamental Design for a Range, of which the following is a specification.

Our new and ornamental design for a range is shown in the accompanying perspective drawing.

The leading feature of our design is in the novel and attractive figures produced thereon.

A subordinate feature is the ornamental shape of the stove with which such figures are combined.

Referring to the drawing, there appears on the oven-plate toward the bottom an oblong panel having a central oblong rosette and curved scroll-like projections at the sides and at each end. Above this panel is a second panel having a fanciful C-shaped downwardly-opening rib and a waved border at the ends. On the oven-door is a central panel having a central rosette and curved scroll-like projections similar to those of the panel described. About the door is a fluted border, which is further ornamented by heavy scroll-like ribs arranged about the same. On the fire-box plate and the ash-door are heavy fanciful C-shaped ribs of varying sizes arranged in an apparently unstudied manner. On the fire-box door is a heavy scroll design which, with its divisions, covers substantially

the entire door. The sides of the projecting front of the stove are ornamented with similar C-shaped fanciful ribs, the contour conforming thereto in a measure. The reservoir-plate is ornamented with fanciful C-shaped ribs of varying sizes, which are interwoven or linked together, and the lower edge of the plate is conformed thereto in contour, giving the same general effect as the ornamental portions of the stove described. Centrally arranged on the warming-oven above is an urn-shaped plate, the base of which has a twisted appearance, and the body thereof is ornamented by inwardly-curved scroll projections. At the center is a fluted rosette, corresponding in general effect to that upon the oven-door and the panel at the bottom. On the warming-oven brackets are ornamental plates made up of ornamental C-shaped ribs arranged somewhat like a monogram.

Having thus described our invention, what we claim as new, and desire to secure by Letters Patent, is—

The ornamental design for a range, substantially as herein shown and described.

In witness whereof we have hereunto set our hands and seals in the presence of two witnesses.

GEORGE W. COPE. [L. S.]
WILLIAM L. BERTRAM. [L. S.]
